[57] CLAIM

The ornamental design for a combined telephone, clock, radio and television receiver, as shown and described.

DESCRIPTION

FIG. 1 is a front, top and right side perspective view of a combined telephone, clock, radio and television receiver showing our new design;

FIG. 2 is a rear, bottom and left side perspective view thereof, the cord has been omitted for ease of illustration; and

FIG. 3 is a front, top and right side perspective view thereof with the antenna in raised and slightly extended position and with the telephone handset removed from the unit base.

Fig. 1
